AIR-OPERATED DUMPER ADJUNCT FOR TOBACCO FEEDER

Edwin L. Wilding, Louisville, Ky., assignor to
Griffin & Company, Louisville, Ky.

Continuation-in-part of design application Ser. No.
551,975, Feb. 21, 1975. This application Sept. 12, 1975,
Ser. No. 612,929

Term of patent 14 years

Int. Cl. D15—03

U.S. CL. D15—28

Fig. 1

Fig. 2

Fig. 3

Fig. 4

Fig. 5

Fig. 6

FIG. 1 is a right side view of an air-operated dumper adjunct for tobacco feeder in one position;

FIG. 2 is a right side view of the dumper in an alternate position; the left side views of the dumper constituting corresponding opposite hand views of FIGS. 1 and 2;

FIG. 3 is a top view of the dumper of FIGS. 1 and 2;

FIG. 4 is a rear view of the dumper of FIG. 1;

FIG. 5 is also a rear view of FIG. 4 in an alternate position corresponding to the dumper position as in FIG. 2; and

FIG. 6 is a perspective view of the dumper of Fig. 1.

FIGS. 3, 4, and 5 show the dumper's hopper broken away to accommodate the drawing scale to the paper. In a typical environmental use, the dumper hopper is about five times as long as it is high as viewed in FIG. 1.

A characteristic feature of my invention is a specific combined mounting and actuating mechanism for the dumper's hopper, as shown in the drawings for mounting

the dumper hopper to a feeder and actuating it to and from its alternate position. The dumper is typically utilized to feed tobacco onto a conveyor mechanism of a tobacco feeder.

This application is a continuation-in-part of my previous copending U.S. application Ser. No. 551,975, filed Feb. 21, 1975.

I claim:

The ornamental design for an air-operated dumper adjunct for tobacco feeder, substantially as shown and described.
